CLAIM

The ornamental design for a brooch, as shown and described.

DESCRIPTION

FIG. 1 is a front view of a brooch of the new design; FIG. 2 is a bottom view of the brooch;

FIG. 3 is a perspective view of the brooch;

FIG. 4 is a top view of the brooch;

FIG. 5 is a side view of the brooch; and,

FIG. 6 is another side view of the brooch.

The back of the brooch is unornamented and forms no part of the claimed design.
